(57) **CLAIM**

The ornamental design for an electrically operated power drill, as shown and described.

DESCRIPTION

FIG. 1 is a side view of an electrically operated power drill showing my new design;

FIG. 2 is a top view thereof;

FIG. 3 is the opposite side view of FIG. 1

FIG. 4 is a front view thereof;

FIG. 5 is a rear view thereof; and,

FIG. 6 is a bottom view thereof.

The broken line showing of environmental structure is for illustrative purposes only and forms no part of the claimed design.

1 Claim, 4 Drawing SheetsFIG. 5
